UNITED STATES PATENT OFFICE.

HARRY KELLY, OF HOUSTON, TEXAS.

PNEUMATIC FLUE-EXPANDER.

No. 888,239.

Specification of Letters Patent.

Patented May 19, 1908.

Application filed August 28, 1907. Serial No. 390,485.

To all whom it may concern:

Be it known that I, HARRY KELLY, a citizen of the United States, and a resident of Houston, in the county of Harris and State 5 of Texas, have invented a new and Improved Pneumatic Flue-Expander, of which the following is a full, clear, and exact description.

This invention relates to means for expanding the ends of flues in the flue sheets 10 of a steam or other boiler; and the purpose of the invention is to provide novel details of construction for a flue expander, which will be actuated by air pressure, will effectually affix a flue end in the sheet, will avoid all jar 15 and percussion thereupon, and obviate the contingency of a flue creeping endwise while the operation of expanding the ends thereof is being conducted.

The invention consists in the novel construction and combination of parts, as is hereinafter described and defined in the appended claims.

Reference is to be had to the accompanying drawings forming a part of this specification, in which similar characters of reference 25 indicate corresponding parts in all the views.

Figure 1 is a longitudinal sectional view of the improved flue expander, substantially on the line 1—1 in Fig. 3; Fig. 2 is a transverse, partly sectional view of details, substantially on the line 2—2 in Fig. 1; Fig. 3 is an enlarged transverse sectional view, substantially on the line 3—3 in Fig. 1; Fig. 4 is a longitudinal sectional view on the line 4—4 35 in Fig. 5, showing a slightly changed means for holding the swaging dies in position for use; and Fig. 5 is a transverse sectional view, substantially on the line 5—5 in Fig. 4.

The invention briefly described, comprises a cylinder, a piston slidable therein, a rod extended from the piston at one end of the cylinder, an expandable sectional die, means for supporting the die projected from one end of the cylinder, a tapered pin connected at its smaller end with the outer end of the piston rod, and means for conducting air under pressure into the cylinder at each end of the piston head alternately, and simultaneously exhausting the air pressure at the 45 opposite end thereof, whereby the die is expanded in a flue end by traverse of the tapered pin in one direction, and retracted by a compression spring when the pin is moved in an opposite direction.

In the drawings, 5 indicates a hollow cylinder of suitable capacity, and 6 a piston

slidable in the true bore of the cylinder and forming an air-tight joint therewith.

From the center of the piston 6 a piston rod 7 projects through a packing box 6^b central in one head 6^a of the cylinder, the rod having sufficient length to permit a proper reciprocation of the piston 6. A valve chest 8 is formed or secured on the cylinder 5, having a preferably cylindrical valve 8^a therein formed 60 with ports a—a' that may be caused to register alternately with air ducts b—b' that respectively extend from the bore of the chest 8 toward opposite ends of the cylinder 5, said ducts intersecting the bore of the cylinder 70 near each head thereof, as shown at b² in Fig. 1. An air inlet pipe c, which may be extended to a source of compressed air, opens into the bore of the chest 8. Between the adjacent ends of the air ducts b—b' an exhaust opening d is formed laterally in the chest 8 below the valve 8^a. Said opening, that intersects the bore of the chest, may be controlled by a rotatable movement of the valve. At one projecting end of the valve 8^a, a lever 8^b is secured by one end, and projects at a right angle therefrom, a vibration of the lever correspondingly adjusting the valve.

One means for connecting flue setting dies with the described construction for service 85 consists of the following details: Upon the end of the cylinder 5 from which the rod 7 projects, a bracket frame is secured, said frame consisting of two smaller arms 9, 9 which converge toward their outer ends that 90 are integrally connected together by a collar e said collar having a central opening e'. A swaging die 10, for expanding the end of a flue is a detail of the improvement, and as shown in Figs. 1 and 3, consists of a plurality 95 of similar segments g, that have wedge shaped bodies, which when assembled form a substantially cylindrical die having a tapered bore and a peripheral surface the shape of which is indicated in Fig. 1. Preferably the composite die 10 is formed of eight segments, as represented in Fig. 3; and at one end thereof a bead h is formed, that in use is inserted into the end of a flue that is to be expanded. Near the opposite end of the die a 105 peripheral groove i is formed therein, which receives the laterally bent flanges i¹ upon a series of similar clamps i², that are curved as shown in Fig. 3. In the periphery of the collar e a circumferential groove is formed, 110 and on opposite ends of the clamps i² flanges i³, similar to the flanges i¹ are formed and are

embedded in said circumferential groove. A shallow groove is formed in the exterior surface of the series of curved clamps i^2 between the ends of the same, and in said groove a contractile hoop-like spring i^4 is embedded, which serves to hold the clamps i^2 in clasped engagement with the sections of the die 10, that is thus compressed into normal form for introduction within a flue. A pin 11, for expansion of the sectional die 10, is employed, having a gradually tapered body which is circular in cross section and of such dimensions as adapt it for effective service. The smaller end of the pin 11 is threaded as shown at m in Fig. 1, and when arranged for use, is first passed through the die 10 and then through the opening e^1 , one end of a sleeve nut m^1 being mounted upon said end of the pin. The outer end of the piston rod 7 is threaded as shown at m^2 and receives the other end of the sleeve nut m^1 ; thus connecting the rod and pin in axial alignment with each other.

In operation it will be observed in Fig. 1 that the die 10 is contracted for free insertion into the end of a flue for its expansion, the flue being omitted from the drawings. The piston rod 7 is drawn out of the cylinder 5, thus disposing the piston 6 near the front head of the cylinder, and adjacent to the termination b^2 of the air duct b . It will be seen that if the lever 8^b is moved into the position shown in Fig. 1, the valve 8^a will have its port a so disposed as to connect the air inlet pipe c with the air duct b that extends forwardly, so that the pressure of compressed air will be imposed upon the forward end of the piston 6. The pressure of the inducted air is so graduated by adjustment of the valve 8^a , that the piston will be moved slowly away from the front head of the cylinder 5 and correspondingly draw the pin 11 through the sectional die 10. Obviously the sliding of the pin will cause the die sections g to spread apart and the diameter of the bead h to be correspondingly increased, which will embed the bead in the inner surface of a flue in which the die may have been inserted. To perfect the operation of "setting" the flue end in a flue sheet, the valve 8^a should be rocked by the lever 8^b so as to push forward the piston that has been pressed rearward, which will shove the pin 11 into the position shown in Fig. 1, and thus permit the spring i^4 to close the sectional die 10. The entire device may now be turned so as to dispose the sections of the die at points intermediate the indented portions of the flue; then the expansion of the die is repeated, which will force the bead h into the flue and expand the intermediate portions mentioned. If found desirable, the tool may be changed in position several times and effect a perfectly reliable, continuous joint between the flue end and flue sheet.

In Figs. 4 and 5, the means for holding the die sections g in operative positions on the frame bars 9, 9, as shown, consists in forming a thread e^2 on the exterior of the collar e and providing a cap nut n mounted on said thread. On the capped end of the nut n , an inwardly extended annular flange n^1 is formed, which is entered within the peripheral groove n^2 formed in the end portion n^3 of the die sections g , and in said groove is seated a circular spring n^3 . The groove n^2 is deep enough to receive the said spring that occupies the bottom of said circumferential groove and clasps the die sections g , holding them in contact with each other at their edges.

It will be seen that in operation, the tapered pin 11 will by traverse of the rod 7 into the cylinder 5, cause an expansion of the die sections g , and effect the setting of a flue end in a flue sheet as heretofore described with regard to the construction shown in Figs. 1 and 3.

It will be apparent that the employment of the improved flue expander will effect the expansion of flue ends in flue sheets, without percussion such as results from the use of ordinary expanders that are operated by blows from a hammer, so that the flue will not be injured and will be more durable than if the metal should become crystallized due to vibrations resulting from percussion.

It is frequently the case that flues move endwise, when the operation of setting them is conducted with an ordinary flue setting device that expands by use of blows from a hammer. Should this occur, the flue must be removed by cutting it out, and as this renders it too short it must be pieced out before it can be used.

It will be seen that the flue expander hereinbefore described, will by avoidance of jar, effect the expansion of flue ends without danger of their moving endwise, and enable perfect work to be done with the tool in a rapid, non-laborious manner.

Having thus described my invention, I claim as new and desire to secure by Letters Patent:

1. A flue expander, comprising a cylinder, a piston in the cylinder, means for admitting a motive agent alternately to opposite ends of the cylinder, a bracket projecting from one end of the cylinder and having a central opening at its outer end, an expandable die, one end of which is adapted to enter a flue, means having interlocking engagement with the die and bracket and securing them together, a spring for normally closing the die, and a tapering pin extending through the die and the opening in the bracket, and means for detachably securing the pin to the piston rod.

2. In a flue expander, the combination with a cylinder, a piston in the cylinder, and

means for admitting a motive agent alternately to opposite ends of the cylinder, of arms projecting from one end of the cylinder and connected at their outer ends by a collar 5 having a central opening, an expansible die having a peripheral groove and a bead at its end and adapted to enter a flue, means engaging the collar and the groove of the die and securing them together, a spring for normally closing the die, and a tapering pin extending through the die and opening of the collar and having its end detachably secured to the piston rod.

3. In a flue expander, the combination 15 with a cylinder, a piston in the cylinder, and means for admitting a motive agent alternately to opposite ends of the cylinder, of arms projecting from one end of the cylinder

and connected at their ends by a collar having a central opening and a peripheral groove, 20 a die formed of a plurality of similar sections and having a bead at its outer end and a peripheral groove at its inner end, a plurality of clamps having flanged ends engaging the grooves of the collar and die, a spring en- 25 circling the clamps, and a tapering pin extending through the die and collar and having its ends secured to the piston rod.

In testimony whereof I have signed my name to this specification in the presence of 30 two subscribing witnesses.

HARRY KELLY.
